UNITED STATES PATENT OFFICE.

GEORGE W. SHAW, OF PHILADELPHIA, PENNSYLVANIA.

AUTOMATIC OIL DRAIN.

Application filed December 6, 1923. Serial No. 678,873.

My invention relates to new and useful improvements in an automatic oil drain, which is adapted for draining oil from the oil chambers in housings or casings of the power plants of automobiles, motor boats and the like and has for its primary object to provide an exceedingly simple and effective device of this character which will siphon oil from an oil chamber without the necessity of removing dirty and inaccessible plugs or the like.

Another object of this invention is to provide a siphon having one leg within the oil chamber and the other leg outside thereof, the latter being rotatably adjustable in order to place the siphon in operative or inoperative condition.

Another object of the invention is to provide means for inducing the siphonic action where the crown of the siphon is above the normal low level of the oil to be drained.

A further object of the invention is to provide means for fastening or locking the movable outer leg in an inoperative position.

A still further object of the invention is to provide means for supporting the movable outer leg in an operative position and to protect a portion thereof against damage due to catapulting objects from the roadway.

Other objects of my invention are, to provide an automatic shut off means which will be opened and closed by the movements of the outer movable leg and according to the position thereof; to provide a unique structure that will facilitate the installation thereof, to provide mechanical means for closing the outer leg as a precaution against leakage and avoiding the suction of air during the induction of the siphonic action.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:—

Fig. 1, is a side elevation of a conventional internal combustion engine illustrat-

ing one application of my invention and showing in dotted lines the position assumed by the outer leg when in operative condition.

Fig. 2, is a fragmentary end view thereof. 60

Fig. 3, is an enlarged fragmentary sectional end view of the same illustrating certain details of construction embodied in the device.

Fig. 4, is a fragmentary side elevation of 65 the siphon removed from the engine and illustrating its relation to the locking lug and other component parts.

Fig. 5, is an edge view of the supporting bracket or rest. 70

Fig. 6, is a plan view thereof.

In carrying out my invention as here embodied, 2 represents an oil chamber in a power plant of an automobile, motor boat or the like and although said power plant is 75 here shown only as an engine 3 of the conventional internal combustion type it is to be understood that this is merely a representation illustrating the manner in which the device is used and wherever the words 80 "power plant" are used they are to include all component parts such as engine crank cases, oil sumps, drip pans, transmission casings or housings, differential housings and the like. 85

In the present instance the oil chamber 2 is illustrated as being in the engine crank case 4 having the usual outlet 5 forming a recess 6 below the lowermost level of the bottom of the casing and normally closed 90 by a plug 7.

Within the oil chamber is located the inner leg 8 of the siphon shown as comprising a tube or pipe of any desirable size, shape or configuration, the lower open end of which 95 is located at any desirable point within the oil chamber but preferably arranged so as to project into the recess 6 and its inner leg 8 may be positioned at any angle or may follow the general lines of the casing or 100 housing in which it is located as herein illustrated. The upper end of the inner leg 8 communicates through a hole 9 with the interior of the socket 10, the two being connected in any suitable manner as by being 105 formed integral. The outer end of this socket is opened and projects through a wall of the casing or the housing in which it is installed and is held in place by a nut 11 or its equivalent mounted on the outer end 110

110

of the socket and engaging the outer face of the casing or housing, said nut preferably having threaded connection with said socket.

The outer leg 12 of the siphon is also shown as comprising a tube or pipe and may be of any suitable size, shape or configuration but preferably consists of a spindle portion 13, an intermediate portion 14 at right angles to the spindle portion and a terminal portion 15 at right angles to the intermediate portion and also at right angles to the terminal portion.

The terminal portion 13 of the outer leg projects into the socket 10 and has a hole 16 in the end enclosed within the socket 10 and so positioned as to register with the opening 9 in said socket when the intermediate portion of the outer leg is in substantially a horizontal position and to be out of registration with said opening 9 when the intermediate portion of said outer leg is in a substantially vertical position. The outer leg, and more particularly the spindle portion thereof, is provided with a collar 17 which abuts the outer end of the socket 10 and this is engaged by a recessed ring 18 fastened in position in some suitable manner as by bolts 19 passing through the ring and having threaded connection with the collar and while said collar holds the outer leg in place it permits the same to be rotated. If found desirable the joint or joints formed between the socket 10, the nut 11, the collar 17 and the ring 18 may be suitably packed.

The different legs of the siphon may be made up of a number of sections if found desirable or preferable and when so made may be screw threaded, telescopically or otherwise connected. It is especially desirable that the outer leg of the siphon be made of a number of sections in order to provide said outer leg with a stop cock or valve 20 of any usual or ordinary construction.

In order to hold the outer leg of the siphon in an inoperative position said outer leg is provided with a hasp 21 for coaction with a locking lug 22 supported by some rigid object such as, for instance, the engine block and a pin 23 passing through the hasp and into the locking lug may be used to hold the parts together and a lock 24, such as a padlock, may be passed through both the hasp and locking lug for locking the parts together and thereby prevent unauthorized use of the drainage device.

In order to limit the movement of the outer leg of the siphon in one direction and supporting the same in operative position as well as to protect a portion of the outer leg of the siphon and more particularly the joint at the crown of the siphon or between its two legs I provide a supporting bracket or rest 25 which is carried by the casing or housing having the oil chamber

therein and said supporting bracket or rest is located in close proximity to the crown of the siphon where it passes through the wall of the casing and extends upward any desirable distance and also horizontally beneath the siphon crown, said horizontal portion forming the rest 26. This supporting bracket or rest is preferably attachable to the casing wall and to this end I provide a flange 27 having holes 28 therethrough for the passage of suitable fastening means such as stud bolts or their equivalent and in order to accommodate the ring 18 said supporting bracket or rest is recessed or shaped so as to project around said ring.

In the form of the invention above described, the crown of the siphon, or in other words the socket 10, is positioned below the normal lowest level of the oil ordinarily in the oil chamber so that when it is desired to drain the oil from said chamber it is only necessary to turn the outer leg of the siphon down to the position shown in dotted lines in Fig. 1 at which time the outer open end of the outer leg will be below the bottom of the oil chamber and since the crown of the siphon is below the lowest level of the oil said oil will immediately begin to flow through the siphon, it being understood that the stop cock 20 is open. The crown of the siphon as well as the outer leg being thus filled with oil the siphonic action will be started and this siphonic action will continue to draw the oil from the chamber until the level of said oil reaches the inner open end of the inner siphon leg. Thus all of the oil, with any foreign matter in suspension or mixed therewith, with the exception of that remaining in the recess 6 below the open end of the inner siphon leg will be drained from the chamber.

As will be obvious this is a relatively simple and clean operation and invites the draining of oil chambers with greater frequency than is now the case and also induces the use of a flushing oil which is thinner than that generally used for lubricating purposes and should be used after the old oil is drained in order to insure a thorough cleansing of the oil chamber.

After the several draining operations have been completed the outer leg of the siphon is positioned, as shown in Figs. 2 and 4 and fastened or locked in this position until it is again desired to drain the oil chamber.

If found desirable once in a while after the oil chamber has been drained and flushed or merely drained the plug 7 may be removed and the small amount of oil remaining in the recess 6 allowed to flow out which may then be done without the likelihood of soiling the hands or clothing to any great extent.

It is a well known fact that a power plant in automobiles, motor boats and the like will

give much better service and last longer where the parts are properly lubricated but due to the uncleanly methods used, the inaccessible position of the parts 4, and the difficulty of removing the parts for draining the oil from a chamber which is used as a reservoir the renewal of this oil is often neglected even after the oil has lost its body, become thin due to heat or has become diluted with gasolene which may have leaked into the oil chamber. By the use of the invention described above these disadvantages are entirely overcome as the removal and flushing of the oil chamber, prior to the refilling of the oil chamber, is a relatively simple and clean operation and may be accomplished quickly even by the layman.

Of course I do not wish to be limited to the exact details of construction as herein shown as these may be varied within the limits of the appended claims without departing from the spirit of my invention.

Having thus fully described my invention, what I claim as new and useful is:—

1. An oil drain comprising the combination with a housing having an oil chamber therein, of an inner siphon leg having its inlet end located in proximity to the bottom of the oil chamber, a socket having an open outer end projecting through a wall of the housing and communicating with the inner

siphon leg, means on the outer end of the socket to hold the same in place and an outer siphon leg having one end journalled in said socket, said journalled end having a hole 35 for registration with the communicating end of the inner leg when said outer leg is in a substantially horizontal position and out of registration with said communication when the outer leg is in a substantially vertical position to shut off the communication between said legs, a collar carried by the outer leg for engagement with the outer end of the socket, a ring embracing said collar to prevent displacement of the outer leg relative to the socket, means to fasten said ring in place, and a stop cock located at a suitable position on the outer leg.

2. An oil drain comprising a siphon for association with an oil chamber and consisting of inner and outer legs, said outer leg being rotatable, and a supporting bracket or rest located in the region of the joint between the two siphon legs and partially surrounding the same with one portion projecting vertically and another portion horizontally, said horizontal portion coacting with the outer leg to limit its downward movement.

In testimony whereof, I have hereunto affixed my signature.

GEORGE W. SHAW.
